UNITED STATES PATENT OFFICE.

JOHN EDWARD ERCANBRACK, OF WOODSTOCK, ILLINOIS.

HOT-AIR FURNACE.

1,130,718.

Specification of Letters Patent.

Patented Mar. 9, 1915.

Application filed May 17, 1912. Serial No. 697,833.

To all whom it may concern:

Be it known that I, JOHN EDWARD ERCANBRACK, citizen of the United States, residing at Woodstock, in the county of McHenry and State of Illinois, have invented certain new and useful Improvements in Hot-Air Furnaces, of which the following is a specification.

This invention relates to hot air furnaces and the especial object of the invention which forms the subject matter of this application for patent is to provide a furnace of simple form and economical construction which will conserve the heat produced and which may be easily and thoroughly cleaned and repaired.

Having the foregoing, and other objects of general utility in view, I have invented a furnace which is made up in sections that may be disconnected where it is necessary to move it through doorways too narrow to accommodate the entire structure, and when it becomes desirable to clean out the flues. I have also designed an air heating appliance in which the furnace proper may be easily disassociated from its casing and conductor pipes by sliding it outwardly; in which the flues are easily and fully controllable and cleanable from the front of the furnace casing; in which provision is made for thoroughly moistening the heated air, and in which the products of combustion are caused to travel over a considerable flue area before escaping to the chimney.

In the accompanying drawing which forms a part of this application, I have shown my improved furnace in an approved form, in the following briefly described views:

Figure 1 is a front elevation of a complete furnace embodying my invention; Fig. 2 is a cross-sectional view on the line 2—2 of Fig. 4, except the casing is omitted; Fig. 3 is a vertical section, on an enlarged scale through the flues at one side of the furnace; Fig. 4 is a vertical section on the line 4—4 of Fig. 1; Fig. 5 is a front elevational view of the furnace proper separated from the casing; Fig. 6 is a horizontal section on the line 6—6 of Fig. 4; Fig. 7 is a plan view on a reduced scale of the track arrangement for sliding the furnace proper in and out of its casing; Fig. 8 is a vertical section on the line 8—8 of Fig. 4; Fig. 9 is an enlarged sectional detail showing the manner in which the casing sides and frame

are connected; Fig. 10 is an enlarged sectional detail showing how the upper and lower sections of the furnace are detachably joined; Fig. 11 is an enlarged fragmentary detail of the roller and track arrangement which constitutes a feature of my invention.

Referring to the details of the accompanying drawings, the casing which forms the outer wall of my improved heating appliance is rectangular in form and made up of a front section 12, side-walls, 12^a, top 12^b, bottom 12^c and rear wall 12^d, all of which are rigidly connected by angle-irons and bolts in any approved manner which will permit easy disconnection between the front 12 and the other sections. In the front wall section 12, is a feed-door 13, an ash-pit door 14, a top flue clean-out door 15, and two side flue clean-out doors 16, all of which may be constructed and arranged to operate in any well-known manner.

At the lower edge of the casing front is an opening 17 through which the track section 22^a may be inserted. Other openings 12^e admit air through the rear wall 12^d. In the top wall 12^b are openings supplied with collars 18 which form connections for suitable heat conductor pipes (not shown). In the rear wall 12^d is an opening 19 which communicates with the smoke pipe (not shown). The water-pan is a trough-shaped receptacle 20 which extends around the sides and back of the furnace and is supported from the casing walls by brackets 20^a. The top of the water-pan is open and is positioned below and in proximity to certain of the hot-air flues as clearly shown in Fig. 8. The smoke-pipe collar 19 is at the rear of a rectangular extension 21 (Fig. 4) of the casing wall 12^d, and is provided with an opening α to the atmosphere which is controlled by a check-draft damper 21^a in a manner well known in the art.

Secured to the inner side of the casing bottom 12^c, is a double rail track 22 which extends from the rear to the front of the casing, and at its forward end connects with an extension track 22^a which is suitably placed either fixedly or removably on the floor in front of the furnace. These track rails receive the rollers 23 which are suitably mounted as shown in Fig. 11 below the inclined bottom wall 27^a of the furnace proper 24, which latter they support on the tracks. The furnace proper 24, is con-

structed with a lower section 24^b and an upper section 24^c the contiguous edges of which are connected by plates 28 which are placed on and overlap the opposite sides of the section edges and are rigidly bolted together by bolts 28^b, in the manner clearly shown in Figs. 5 and 10. In the upper section 24^c, is a feed opening 24^d (Fig. 5) which registers with the opening in the front wall of the casing controlled by the door 13, and in the lower section, 24^b, is an ash-pit opening 24^e, which registers with the casing opening controlled by the door 14. The opening 24^d communicates with fire-box 25 and the combustion chamber 26 above the fire-box, and the opening 24^e communicates with the ash-pit or pan 27 below the fire-box. The walls of the fire-box are lined with fire-brick 25^a, 25^b, the rear bridge wall 25^b, being backed up by an angle-plate 29, the horizontal portion of which forms, with the top wall 30 of the furnace, a smoke outlet 31, which leads to the smoke-flue extension 21, and is controlled by a pivotally mounted damper 31^a which in turn is operated by a damper rod 31^b running forwardly and extending from the front wall of the furnace casing, as indicated in Fig. 4.

Below the smoke flue 31, is a communicating flue 32 formed by the plate 29 and a shelf or partition 33, and controlled by a pivoted damper 33^a which is provided with an operating rod 33^b which passes through and projects from the front casing-wall 12.

At the rear of the bridge wall 25^b, and between it and the back wall 24^a of the furnace proper, is an outlet chamber 34, in the bottom wall 34^b of which, is mounted a damper 34^a, operated by a damper rod 34^c extending from the front of the casing, said chamber serving as an exit for dust from the ash pit and deposits from the products of combustion.

In the side walls 24^b of the furnace 24 are openings 24^e which communicate with the combustion chamber 26, and below the openings 24^b, are similar openings 24^d, which communicate with the outlet chamber 34. Connected with the openings 24^e by collars 35^a, are rectangular flues 35 which extend forwardly and are supported from the furnace walls by 2-piece brackets 35^a and 35^b, as shown in Figs. 5 and 6. Each of the flues is divided into two compartments 35^c, 35^d, by a partition 35^b which extends horizontally from the wall adjacent the flue connections 35^a forwardly the greater portion of the length of said flues but terminating before reaching the front end of the flue so as to leave a passageway for the products of combustion at the forward end of the flue, as shown in Fig. 3. Each flue has two openings 35^e, 35^f, which communicate respectively with the openings 24^e, 24^d, in the furnace walls, the joint being closed by the collars 35^a as shown

in Fig. 6. In the front end wall of each flue 35 is an opening 35ⁱ through which access is had to the interior of the flues when the doors 16 are removed. Rocking grate-bars are suitably mounted below the fire-box 25 70 in any approved manner.

It will be noted that the four wheels 23 form a truck which carries the furnace proper and permits the latter to be drawn forwardly, when the few bolts which connect the walls of the furnace with the casing walls are removed. It should be understood that the front casing wall is connected with its side walls by as few bolts as possible to effect a practically tight joint, but the connection between said front wall and the front of the furnace proper is such that the latter moves forwardly with the casing front wall. It will also be apparent that as the water pan 20 is connected only with the casting side walls it will not be affected by the movements of the furnace proper.

In Fig. 9, I have illustrated a preferred way of detachably connecting the walls of the casing at the corners, in which I use 90 angle-irons 36, flat plates 37, insulating strips 38 and bolts 39, but any other approved method of effecting such connections may be employed, as these are matters of 95 mere mechanical detail.

In using my improved furnace, when a fire is started in the fire-box 25, the damper 31^a should be opened and the damper 33^a closed, which positions will be just the reverse of those shown in Fig. 4. In this position of the dampers the draft will be directly from the ash pan 27 through the fire-box 25, combustion chamber 26, smoke-passage 31 and outlet 19 to the chimney. When the fire is in condition to require less draft, 105 the damper 31^a should be closed and 33^a opened, whereupon the smoke and products of combustion will pass from the combustion chamber 26, out the openings 24^e, through the connections 35^a, and traverse the flue 110 compartments 35^f, 35^g, before passing out the opening 35^h into the chamber 34 and thence to the chamber 32 and thus to the opening 19. As the walls of the flues 35 are entirely inclosed by the casing walls, the air 115 within the latter which has entered through the openings 17 and 12^e will be effectively heated before passing out the conductor openings 18. Any soot falling in the chamber 34 will be discharged by the action of 120 gravity into the ash-pan upon opening the damper 34^a.

It will be noted that the only laterally extending flues in my improved furnace are the short connections between the flues 35 and the combustion chamber and as these are of limited area they can be effectively cleaned by introducing a suitable tool through the door opening 24^d, and the flue clean-out 125 openings covered by the doors 16.

Having thus described my invention what I claim as new, is:—

A furnace comprising a casing adapted to contain an ash receiving compartment, a grate suspended above the same, a fire box located above said grate, a horizontal smoke-flue located on each side of said fire box, said flues having a plurality of outlet ports at one end thereof, one of which connects with the upper portion of the fire-box and the other of which connects with the smoke outlet, and a baffle plate in each smoke-flue extending from between said outlet ports to a

point adjacent the passageway from said fire-box, an outer casing into and out of which said first-mentioned casing is adapted to be moved, and a smoke conduit connected with the smoke outlet ports of said inner casing. 15

In testimony whereof I affix my signature 20 in the presence of two witnesses.

J. EDWARD ERCANBRACK.
